Attorney.

UNITED STATES PATENT OFFICE.

BURCHARD D. THOMPSON, OF BRADFORD, PENNSYLVANIA.

NUT-LOCK.

SPECIFICATION forming part of Letters Patent No. 787,804, dated April 18, 1905.

Application filed January 20, 1905. Serial No. 241,978.

To all whom it may concern:

Be it known that I, BURCHARD D. THOMPSON, a citizen of the United States, residing at Bradford, in the county of McKean and State of Pennsylvania, have invented certain new and useful Improvements in Nut-Locks, of which the following is a specification, reference being had therein to the accompanying drawings.

10 My invention relates to improvements in nut-locks, and pertains more particularly to that class in which a transverse key is adapted to engage the threads of the bolt.

The object of my invention is to provide a 15 nut-lock of this character, in which the transverse key carried by the nut is wholly within the same and is locked therein by an additional lock, which is also wholly within the nut.

20 Another object of my invention is to provide a lock of this character in which interlocking of the key and lock holds the two in their locked or unlocked position against rotation.

25 In the accompanying drawings, Figure 1 is a perspective view of the nut applied to the bolt and locked thereon and the operating key inserted therein. Fig. 2 is a transverse sectional view taken on the line 2-2 of Fig. 1.

30 Fig. 3 is a longitudinal sectional view taken on the line 3-3 of Fig. 2. Fig. 4 is a transverse sectional view showing the key turned so that the nut is free to turn. Fig. 5 is a detached perspective view of the key, the locking-key, and the key-locking means, showing their relative positions.

Referring now to the drawings, A represents a bolt broken off and having the usual screw-threaded portion *a*, upon which is 40 screwed a nut B, which is provided with the usual screw-threaded opening *b*, through which the bolt is adapted to pass. The said nut is provided with a transverse recess C, extending from one side thereof through the 45 nut and intersecting the opening *b* at one side and extending beyond the same, but not through the wall of the opposite side of the nut. This recess is simply a hole bored into the nut, and loosely fitting into the said recess 50 is a round key D, which is adapted to freely

rotate, and said key is of a length to extend from the inner closed end *c* of the recess D out to and flush with the side wall of the nut, and thus there is nothing projecting beyond the nut. The end *d* of the key is reduced 55 and squared, as shown, and thus a key E may be inserted in the recess for turning the thread-engaging key. The said key opposite that portion of the recess which intersects the threaded opening in the nut is provided 60 on one side with a curved cut-away portion F, which corresponds to the curvature of the bolt, and thus when said key is so turned that this rounded portion registers with the screw-opening in the nut the nut is free to turn on 65 the bolt. The said key is provided with laterally-extending tooth portions G, having their teeth extending at right angles to the cut-away portion, and thus when said toothed portion is turned across the opening *b* in the 70 nut the said teeth engage the threads of the bolt and prevent the nut from being turned. In order to prevent the said key from being turned accidentally or by pressure on either the nut or bolt, and thus allowing the cut-away 75 portion to register with the threads, I provide a transverse lock K, which engages the end of the thread-engaging key at right angles thereto and locks the key in either of the above-mentioned positions. 80

The nut B is provided with a recess I, which extends inwardly from one side of the nut at right angles to the recess C, carrying the key D, and squarely intersects it and extends inwardly beyond the same. The said key D 85 adjacent its inner end is provided with a cut-away portion forming three flat faces *i*, *i'*, and *i''*, but leaving a small portion J of the round key at the end, as clearly shown in Figs. 2, 4, and 5, forming the locking-shoulder to prevent the key from sliding from the nut. The recess I, intersecting the key-carrying recess, is provided at its inner end with a coil-spring J', which rests loosely therein, and fitting loosely within the outer end is the 90 key-locking member K. The said member is of a cylindrical form and is provided with the transverse cut-away portions *k* and *k'*. The portion *k*, being adjacent the inner end thereof, and the cut-away portion *k'* adjacent the 95 100

outer end, is wider and much deeper, as hereinafter more fully described, the positioning of the two recesses being such that the cut-away portion k' when the lock is forced in 5 against the tension of the spring will be opposite the cut-away portion of the lock. Releasing the lock brings the lower shallow cut-away portion k in engagement with one of the three flat faces i , i' , and i'' of the cut-away portion of the key, and thus the key is prevented from being turned and is rigidly locked in any position with either the teeth 10 in engagement with the threads of the bolt and locking-nut thereon or with the curved 15 portion opposite the threads, so that the nut is free to turn on the bolt.

By this structure I have taken the ordinary bolt and nut and drilled the two intersecting recesses in the nut and placed the spring and 20 interlocking members therein, which are adapted to hold each other in their operative positions and in which the same may be readily placed therein and removed, as desired, when using the nut when a lock is not 25 desired.

In order to insert the two interlocking members in the nut, the same is removed from the bolt and the spring J' is first inserted. The lock K is then placed therein, 30 the spring holding the outer edge thereof flush with the side of the nut. The key D is then placed therein, bringing the end against the lock K opposite the cut-away portion k . The member K is next depressed, which brings 35 the enlarged cut-away portion k' opposite the end of the key D , which allows of the same being forced all the way into the recess and releases the lock K , which brings the cut-away portion k in engagement with one of 40 the flat faces i , i' , and i'' , and thus the key is locked in the said position. To turn the key, the instrument E is first inserted, as shown in Fig. 2, and the lock K forced inward, as 45 shown in Fig. 4, which brings the cut-away portion k opposite the flat faces i , i' , and i'' , and thus the key may be turned so that the nut is either free to turn or locked on the bolt.

Having thus described my invention, what I claim, and desire to secure by Letters Patent, is—

1. The combination with a bolt, of a nut thereon, a transverse rotatable thread-engaging member within the nut, and a transverse sliding key entering the nut and adapted to lock said member within the nut.

2. The combination with a bolt, of a nut thereon, a transverse rotatable thread-engaging member within the nut, and a transverse sliding key entering the nut and adapted to lock said member within the nut and also against rotation.

3. The combination with a bolt, of a nut thereon, a transverse rotatable thread-engaging member within the nut, and a transverse sliding key entering the nut and inter-

locking with rotatable member and adapted to hold the same within the nut and against rotation when engaging the threads.

4. The combination with a bolt, of a nut thereon, a transverse rotatable thread-engaging member within the nut, and a transverse sliding key entering the nut and normally outwardly held and interlocking with the rotatable member and adapted to hold the same within the nut, and also against rotation when the same is engaging the threads of the bolt.

5. The combination with a bolt, of a nut thereon, a transverse member intersecting the opening in the nut and having a cut-away portion to allow the threads of the bolt to pass, said member having on another side the thread-engaging teeth, and a member carried by the nut and extending at right angles to the transverse member and adapted to lock said member within the nut and to lock it with either the cut-away portion or teeth opposite the threads of the nut.

6. The combination with a bolt, of a nut thereon, a transverse key carried by the nut and a transverse member interlocking with the key and holding each other within the nut.

7. The combination with a bolt, of a nut thereon, a transverse key loosely extending within the nut and adapted to engage the threads of the bolt, and a transverse member extending at right angles to the key and interlocking with the same, and holding each other within said nut.

8. The combination with a bolt, of a nut thereon, a transverse key carried by the nut and a transverse member interlocking with the key and holding each other within the nut, and means carried by the transverse member for locking the key in its adjusted position.

9. The combination with a bolt, of a nut thereon, a transverse rotatable key carried by the nut and adapted to engage the threads of the bolt, a transverse member interlocking with the key and holding each other within the nut, and means carried by the transverse member for holding the key in its adjusted position against rotation.

10. The combination with a bolt, of a nut thereon, a transverse rotatable key carried by the nut and having a concaved face to allow the threads of the bolt to pass, teeth carried by said key and adapted to engage the threads of the bolt, an outwardly spring-pressed member interlocking with the key and holding each other within the nut, and means carried by said member for holding the key in its rotating position, and means carried by said member for allowing the rotation of the key.

11. The combination with a bolt, of a nut thereon and having a transverse opening intersecting one side of the bolt-opening, a ro-

tatable transverse key in said opening wholly within the nut, said key having one face thereof opposite the bolt-opening cut away and another face provided with transverse thread-engaging teeth, the inner end of the key provided with a cut-away portion forming three flat faces, said nut having a second opening at right angles to the key-opening and squarely intersecting the same, a spring 5 within the inner end of said opening, a member within said opening and normally outwardly spring-held, said member having a deep transverse cut-away portion adjacent its outer end and a shallower cut-away portion 10 communicating therewith and extending adjacent the inner end of said member, and adapted to interlock with the cut-away portion of the key, and to hold the same against rotation, and when the said member 15 is depressed the enlarged cut-away portion registering with the key and allowing of the rotation thereof.

12. The combination with a bolt, of a nut thereon, a transverse member loosely extending within the nut and adapted to engage the threads of the bolt, and a transverse key outwardly spring-pressed, and interlocking with the transverse member, and holding each other within said nut.

13. The combination with a bolt, of a nut thereon, a transverse rotatable member therein and adapted to engage the threads of the bolt, and a transverse outwardly spring-pressed key interlocking with the transverse member and holding each other within the nut.

14. The combination with a bolt, of a nut thereon, a transverse rotatable member therein and adapted to engage the threads of the bolt, and a transverse sliding key adapted to lock the member against rotation.

15. The combination with a bolt, of a nut thereon, a transverse rotatable member therein and adapted to engage the threads of the bolt, and a sliding key extending at right angles to the said member and interlocking with the same and adapted to lock said member in its rotated position, and the interlock-

ing of the member and key adapted to hold each other within the nut.

16. The combination with a bolt, of a nut thereon, a transverse rotatable member therein and adapted to engage the threads of the bolt, and a sliding key extending at right angles to the said rotatable member, and interlocking with the said member, a spring normally holding the said key in an outward position, and the interlocking of the key adapted to hold the member in its rotated position and holding each other within the nut.

17. The combination with a bolt, of a nut thereon and having a transverse opening intersecting one side of the bolt-opening, a rotatable transverse member in said opening wholly within the nut, the outer end of said key having a reduced squared portion for the reception of a key, said member having one face thereof opposite the bolt-opening cut away and another face provided with transverse thread-engaging teeth, the inner end of the said member provided with a cut-away portion forming three flat faces, said nut having a second opening at right angles to the first opening and squarely intersecting the same, a coiled spring within the inner end of said opening a member within said opening and normally outwardly spring-held and held therein by interlocking with the thread-engaging member, said member having a deep transverse cut-away portion adjacent its outer end and a shallower cut-away portion communicating therewith and extending adjacent the inner end of said member, and adapted to interlock with the cut-away portion of the key and to hold the same against rotation, and when said key is depressed the enlarged cut-away portion registering with the thread-engaging member and allowing of the rotation thereof.

In testimony whereof I affix my signature in presence of two witnesses.
